UNITED STATES PATENT OFFICE.

CHESTER W. M. SMITH, OF SAN FRANCISCO, CALIFORNIA.

METALLIC RAILWAY-CAR.

SPECIFICATION forming part of Letters Patent No. 439,085, dated October 21, 1890.

Application filed July 22, 1889. Serial No. 318,259. (No model.)

To all whom it may concern:

Be it known that I, CHESTER W. M. SMITH, a citizen of the United States, residing at San Francisco, in the county of San Francisco and State of California, have invented a certain new and useful Improvement in Metallic Railway-Cars, which is fully set forth in the following specification, reference being had to the accompanying drawings, in

10 which—

Figure 1 represents a side elevation of a car embodying my improvements, partly in section at one end; Fig. 2, a detail plan section taken on the line 1 1 of Fig. 1; Fig. 3, a 15 similar bottom plan section taken on the line 2 2 of Fig. 1; Fig. 4, a cross-section taken on the line 3 3 of Fig. 1; Fig. 5, a detail cross-section at one of the lower corners of the car; Fig. 6, a similar section at one of the upper 20 corners of the car; Fig. 7, a detail side elevation of the car, showing a slight modification; and Fig. 8, a detail cross-section of the same, taken on the line 4 4 of Fig. 7.

In the drawings, Fig. 1 is upon a scale by 25 itself; Figs. 2, 3, 4, 7, and 8, upon the same scale, but enlarged from Fig. 1; and Figs. 5 and 6, upon the same scale, but still further enlarged.

My present invention relates to railway- 30 cars constructed almost or entirely of metal; and it consists in certain improvements upon the car described and shown in Letters Patent No. 359,640, heretofore granted to me, dated March 22, 1887.

35 I will describe in detail and as fully as necessary to an understanding of the said improvements the construction of a car embodying my present invention, and will then point out more definitely in claims the special improvements which I believe to be new and 40 wish to secure by Letters Patent.

In the drawings, A A represent the sills running the length of the car, upon which the car-body rests and which are themselves 45 mounted upon the trucks in any usual way. These sills are made of metal, preferably steel, and are hollow or tubular. In the drawings they are shown of rectangular form; but this is a matter of choice. If desired, 50 some of these sills may be solid, although I prefer to have all of them tubular for pur-

poses of strength and lightness. The body of the car is made, as in my former patent, from plates of metal, preferably steel; but the mode of construction is somewhat different. The sides B, instead of being made from single plates, are composed of a series of short plates b, which are lap-riveted together at their edges, as shown in the drawings. The floor-plate C is also made in similar sections united by lap-riveting, and preferably in the same plane as the joints of the sides. Instead of separating the floor-plates and the sides at the lower corners of the car, as in my former patent, I extend the floor-plate outward to the full width of the car and extend the lower edges of the side plates downward until they rest directly upon the flooring, as seen in Figs. 4 and 5 of the drawings. Plates D and D' are here employed, as 65 in my former patent, to make the lower side beams of the car proper. These plates are bent as in said former patent, the outer one D having a single right-angled bend and the inner one D' having the flanges d d' at its 70 lower and upper edges, respectively, whereby a tubular beam is obtained and a suitable fastening for the side plates and floor-plates, which are riveted to these two angular plates, as shown in Figs. 4 and 5. These corner- 75 beams run the entire length of the car, as before, and are bent inward at the respective ends of the car, and these ends are closed by suitable plates at each end of the car. Openings d² are, however, let into these tubes at 80 each end from the outside of the car, as shown in Figs. 1 and 2, which openings are supplied with threaded plugs d³, by which they are closed whenever desired. In this way I provide for circulation through these tubular 85 beams, either of air from the outside by simply removing the plugs or of steam or hot air from any suitable supply, by making a suitable coupling from the tubes in one car to those of another. These tubular beams therefore become the means for ventilating and 90 heating the cars.

The complete flooring of the car is made up from several layers. The floor-plate C has been mentioned already. Below this plate is 95 a thin layer of metal c, which rests immediately upon the sills and extends from one side

of the car to the other, projecting out underneath the horizontal part of the plate D flush with the upright portion thereof, as seen in Fig. 5. It is obvious that this will leave a space between this lower layer and the metal plate C, and this space is occupied by a sheet of compressed paper-pulp or papier-maché c' , which fills the entire space between the two layers mentioned and between the inner edges of the two plates D. This paper-pulp makes a very desirable packing for these cars, and is preferably made completely fire-proof by treatment with any well-known solution for this purpose. Immediately above the floor-plate C is a layer c^2 of any suitable material. A sheet of paper-pulp is a desirable material for this upper layer. Similar tubular side beams are formed at the upper corners of the car by outer plates E and inner ones E', which are like those at the corners below and in my former patent.

The roof F of the car is also made from several sections f instead of a single sheet, as before, these sections being lap-riveted like the sides and in the same plane. The outer edges of the roof and the upper edges of the side plates are embraced by the two tube-plates E and E', the same as before, and are in the same manner riveted to the side plates; but here also I bring the edges of these two inner plates together by extending the roof-plates outward until they meet the outer plate E and carry up the side plates until their upper edges meet the roof-plates, as seen in Fig. 6 of the drawings. With this arrangement of the plates within the tubes at the four corners of the car a stronger joint is obtained and also a stronger tube, so that taken together the car is materially strengthened and better able to resist serious shocks. The tubular beams or girders at the upper corners of the car are also closed at their ends, but have openings e let into them from the outside, which are closed by screw-plugs e' , the same as below and for similar purposes.

The section-plates of the roof are bent so as to provide the usual dome, and immediately below the highest portion of the dome is a metal plate G, which extends from one side of the dome to the other and runs the whole length of the car, leaving a space between it and the top of the dome, as seen in Figs. 1 and 4. This plate extends outside of the car at each end, being bent downward, as at g , under the hoods over the car-platforms, and the roof-plates are also carried downward in a similar way, so as to provide an opening F' into this space in the top of the dome at each end of the car. There is thus provided an air-space the entire length of the dome, through which air will freely circulate when the cars are in motion, the openings into these spaces being under the hoods at the ends of the car. Lining-plates H are bent to conform to the roof under which they are placed and extend from the inner tube-plates E' inward and upward to the plate G, which rests upon

their upper edges, and between the outside roof-plates and this lining a layer of compressed paper-pulp h may be inserted. The plates are riveted together at the corners and at the points where they join at the dome.

The sides of the car are also provided with interior lining-sheets I, which are preferably of the same material as the outside sheets, but may be considerably thinner, and are arranged a little distance from the latter, so as to leave a space between the two, which is filled with a packing J of the same material heretofore mentioned—that is, compressed paper-pulp or papier-maché. This packing of the sides of the car provides insulation against both heat and cold, and also serves to deaden the sound, which has been found somewhat objectionable in metal cars. The introduction of this packing at the floor and roof of the car is also for the same purposes.

The interior lining-sheets are sectional, the same as the exterior plates forming the sides of the car, and preferably the joints are in the same plane with the latter, as seen in Fig. 2 of the drawings, this arrangement being for convenience in building and repairing the car. The interior of the car may be finished in various ways. It is a matter largely of taste.

In Figs. 7 and 8 of the drawings I have shown a slight modification in the structure illustrated by the other figures. It relates entirely, however, to the lower corner of the car, and consists in extending the side plates b down to the floor, as heretofore described, and then bending them inward at right angles, so as to provide a horizontal section b' , upon which the edges of the floor-plates directly rest, as seen in Fig. 8 of the drawings. In this construction the outer angular plate used in the construction already described is dispensed with, and the sides of the car present a smooth plane surface to the very bottom edge, as seen in Figs. 7 and 8. The advantage of this modification is that no seam is offered for the possible entrance of water, which might occasionally occur at some points in the construction shown in Fig. 5 if there should be carelessness in keeping this joint carefully protected by paint or other suitable material. In this modification, however, it is obvious that the lower corners of the car are not as strong as in the other construction, and for this reason it is not suitable for heavy cars, but may be made satisfactory even for the latter structures by strengthening internally, which may be done by any suitable process, as an angular plate put within the tube.

In the construction of the car from sectional plates, as described above, important advantages are obtained. The plates themselves are more readily manufactured, and so more cheaply obtained. The car is more easily built, and at the same time is, if anything, stronger than under the construction in my former patent, for the lap-riveting of the sec-

tions together makes the strongest kind of construction possible. It is also a great convenience in repairing, for if a car is damaged at some point it is only necessary to take out 5 the damaged section and replace with a new plate, so that instead of practically destroying the entire body of the car it may be repaired as readily as a steam-boiler.

In the details of construction there may be 10 many modifications, and I do not wish to be understood as limiting myself to the special details herein shown and described.

Having thus described my invention, what I claim as new, and desire to secure by Letters Patent, is—

1. In metal railway-cars, the metal tubular side beams curved to form the lower corners of the car-body, closed at their ends, but provided with apertures opening into them at 20 each end from the outside of the car, substantially as and for the purposes specified.

2. In metal railway-cars, the metal tubular side beams curved to form the upper corners of the car, closed at their ends, but provided 25 with apertures opening into them from the outside of the car, and provided with removable closing-plugs, substantially as and for the purposes specified.

3. In metal railway-cars, the tubular side 30 beams at the lower corners of the car, closed at their ends and provided with openings d on the outside of the car, in combination with threaded plugs d^3 , by means of which said openings may be closed, substantially as and 35 for the purposes specified.

4. In metal railway-cars, the floor-plate C, extending outward the full width of the car on each side, in combination with the side plates B, extending downward to the bottom of the car and resting upon the floor-plates, 40 and the bent plates D D', substantially as and for the purposes specified.

5. In metal railway-cars, the side plates B, in combination with the roof-plates F, bent to the form of the roof and extended outward 45 to rest directly upon the upper edges of the side plates, and the bent plates E and E', substantially as and for the purposes specified.

6. In metal railway-cars, the sheet-metal roof F, bent to the required shape of the roof, 50 in combination with a metal plate G, arranged just underneath the top of the roof-dome, extending the entire length of the car and outward and downward under the hoods at the ends, whereby openings are provided into the 55 space between the two plates under each hood, substantially as and for the purposes specified.

7. In metal railway-cars, the double-walled sides composed of several plates lap-riveted together, in combination with the flooring 60 composed of similar plates lap-riveted together and the roof composed of similar plates also lap-riveted together, the joints of the sections of these several parts of the car being arranged in practically the same plane, 65 substantially as and for the purposes specified.
